UNITED STATES PATENT OFFICE.

CHARLES A. PRATTE, OF DENVER, COLORADO, ASSIGNOR OF ONE-HALF TO CRISSEY J. CREWES, OF DENVER, COLORADO.

VACUUM-SANDER.

1,263,106.

Specification of Letters Patent. Patented Apr. 16, 1918.

Application filed June 29, 1917. Serial No. 177,704.

To all whom it may concern:

Be it known that I, CHARLES A. PRATTE, a citizen of the United States, residing at the city and county of Denver and State of Colorado, have invented certain new and useful Improvements in Vacuum-Sanders; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to improvements in vacuum air sanders, more especially adapted for use in connection with locomotives on railways. My present construction consists in connecting a number of air nozzles directly with conduits mounted on the sand box of the locomotive and projecting thereinto, being open at both extremities and extending both inwardly and outwardly from the box. The outer extremities of these conduits are equipped with the air nozzles which 20 are vertically disposed and downwardly directed. The partial vacuum produced by the air rushing through these nozzles at right angles to the axes of their conduits, causes 25 the sand to move outwardly from the sand box through the conduits and into the path of the air from the nozzles, which then drives the sand downwardly through relatively long pipes which deliver it to the track 30 rails in the vicinity of the locomotive drive wheels.

35 An important feature of my present invention consists in equipping the inner extremity of each conduit, above its sand inlet, with a chamber which is formed by threading into the conduit a tubular member whose lower extremity is open and whose upper end is closed. This chamber performs an important function in the operation 40 of the sander as I have demonstrated in practice.

Having briefly outlined my improvement I will proceed to describe the same, reference being made to the accompanying drawing in 45 which is illustrated an embodiment thereof.

In this drawing:

Figure 1 is an outline side elevation of a

locomotive equipped with my vacuum sanding apparatus.

Fig. 2 is a horizontal section taken through 55 a sand box equipped with my improved construction. This is a section taken on the line 2—2, Fig. 1, looking downwardly, the parts being shown on a much larger scale.

Fig. 3 is a section taken through one of 60 the conduits connected with the sand box. This section is taken on the line 3—3, Fig. 2, viewed in the direction of the arrow, the parts being shown on a still larger scale. In this view the sand box is also shown in section. 65

The same reference characters indicate the same parts in all the views.

Let the numeral 5 designate the sand box which is mounted on top of the locomotive 70 6 in the usual position, the sand box being of usual or ordinary construction except for the fact that it is equipped with my improvement, which will now be described.

As illustrated in the drawing, the sand box 75 is provided with four openings 7, which are equidistantly spaced around the box, which is circular in cross section. Through each of these openings is passed a conduit 8 which is threaded at its inner and outer extremities, 80 as shown at 9 and 10. The inner extremity of each conduit member 8 is equipped with a downwardly turned elbow 12, whose lower extremity is open and occupies a position a short distance above the bottom 13 of the 85 sand box. In order to regulate the length of the downwardly extending portion of this elbow it may be provided with an adjustable nipple 14, which is threaded thereinto and capable of vertical adjustment for the purpose stated. As all sand boxes are not of uniform depth it may be necessary to regulate the length of the downwardly extending arm of the elbow in order that its lower extremity may occupy the proper position 90 with relation to the bottom of the box, in order to remove the sand therefrom to the best advantage. These conduits are so arranged in the box and upon the same, that all of the sand may be removed from the 95 box through their agency, and it is for this reason that the lower extremities of the elbows and the conduits should occupy the proper position with reference to the bot-

tom of the box, since the vacuum pull, incident to the use of the air nozzles, as herein-after explained, must be sufficient to draw the sand upwardly from the bottom of the 5 box.

The elbow 12 is provided with an opening directly above the adjustable nipple 14, said opening being interiorly threaded to receive the lower extremity of a tubular member 4, 10 which extends above the elbow, its upper extremity being closed by a screw-cap 2. This tubular member forms a chamber which contributes in an important manner to the proper performance of the function of the 15 apparatus. It is, of course, normally filled with air at atmospheric pressure when the sander is not in use. Hence, when the use of the sander commences and air is discharged across the outer extremity of the 20 conduit through the medium of the nozzle, as herein-after explained in detail, the air is drawn from the said chamber and acts in an important way to cause the sand to travel from the box through the conduit.

25 The outer portion 10 of the conduit member 8 passes through the opening 7 in the wall of the sand box. To the inner surface of this wall is applied a gasket or rubber washer 15, and to which is applied a metal 30 washer 16, the latter being in turn engaged by a securing nut 17, which when screwed tightly against the adjacent washer holds the washers 15 and 16 securely in place and forms a tight joint around the opening in 35 the wall of the box, through which the conduit member passes. The outer part of the threaded portion 10 of the conduit is also equipped with a washer 18, which engages the outer surface of the wall of the sand box. It will be understood that the washers 40 18 and 16 must have their inner surfaces curved to conform to the curvature of the circular wall of the box, in order to fit the same closely. Applied exteriorly to the 45 conduit member 8 is an approximately spherical member 19, which is threaded upon the outer extremity of the member 8 and screwed tightly against the washer 18. This member 19 has an opening 20 which registers with the opening of the conduit member 8, to receive the sand which passes outwardly therethrough from the sand box. The member 19 is also provided with a bottom opening 21 from which leads a 50 downwardly extending sleeve 22 into which is threaded the upper end of a pipe 23 which leads downwardly to the track either in front or rear of the locomotive drive wheels 24.

60 It will be understood that each of the conduits mounted on the sand box and composed of the parts above explained, is substantially identical in construction, so that the description of one is a description of all. It will be also understood that the

sand issuing from two of these conduits, *i. e.*, the front pair, will pass through two conduits 23 downwardly to the track in front of the locomotive drivers, while the sand which passes out of the box through the two other conduits, will pass downwardly through other pipes 23 to the track in the rear of the drivers to be utilized when the locomotive is backing. Each part 70 19 is provided at the top with a relatively small opening 64 which has a sleeve 25 extending upwardly therefrom into which is screwed a threaded portion 26 of a nozzle 27. This nozzle also has an upper threaded portion 28 which is threaded into the lower member 29 of a two-part feature 30, its co-operating part 31 being connected with the part 29 by means of a coupling member 32. This feature, composed of parts 29 and 31, 75 contains a chamber 33 into which the upper tapering extremity 34 of the nozzle 27 projects. Into the upper extremity of the feature 30 is screwed an air pipe 35 which is in communication with the main pipe 36 connected with the air for supplying the 80 air brakes of the train. The lower portion of the nozzle 27 is relatively long and tapers downwardly, its lower extremity passing below the horizontal center of the member 19 and being directed toward the center 85 of the pipe 23.

The passage through the nozzle 27 is relatively small and the air as it escapes from the lower extremity thereof has sufficient force to produce a partial vacuum within 90 the chamber of the member 19, of such strength as to draw the sand 3 from the sand box and cause the same to travel upwardly through the elbow 12 and outwardly through the conduit member 8 into the part 100 19, where it is acted upon by the downwardly directed air current and forced through the pipe 23 to the desired location, *i. e.*, the track rail in proximity to one of the drive wheels. From the foregoing description the use and operation of my improved vacuum air sander will be readily understood.

There are two pipes which supply air to the nozzles 27. One of these pipes extends 115 forwardly to a branch pipe 35. If it is desired to sand the track in front of the front drivers 24 of the locomotive a valve 42 is opened which allows the air to pass from the main pipe 43 through the pipe 36 120 whose forward extremity is connected with the forwardly located branch pipe 35; while if it is desired to deliver the same to the track rails in the rear of the rear drivers, a valve 44 is opened, which allows the air 125 to pass through the other pipe 36 to the rearwardly located branch pipe 35 supplying the rearwardly located nozzles 27. It has been proven by actual demonstration that my present improvement is exceedingly efficient 130

as a sanding apparatus, and this, together with its simplicity and economy of construction makes it a highly desirable device for the performance of the track sanding 5 function.

By reference to Fig. 2 of the drawing it will be observed that the conduits mounted on the sand box are radially arranged and that their inner extremities extend into the 10 central portion of the box. This is important for the reason that the sand in the central portion of a receptacle of this character is always dry, while the portion adjacent the wall is frequently caked or hardened, due to the presence of moisture or 15 for other reasons; while in the center of the box no such difficulty exists, and by first removing the sand from the central portion, that surrounding the center and nearer the 20 wall of the box is more easily removed and brought under the influence of suction through the conduits.

Having thus described my invention, what I claim is:

25 1. A sander comprising in combination with a sand box, a conduit passing through an opening formed in the wall of the box, one extremity of the conduit being located within the box and the other outside thereof, the inner extremity of the conduit having a chamber in connection therewith, the outer extremity of the chamber being closed, and an air nozzle mounted on the outer extremity of the conduit and arranged to discharge air across the axis thereof.

30 2. The combination with a sand box, of a conduit passing through an opening formed in the wall of the box, the extremities of the conduit being open, the inner extremity being located within the box, directed downwardly, and equipped with a communicating chamber closed at its outer extremity, while the outer extremity of the conduit is equipped with an air nozzle arranged to discharge air across the axis of the conduit for the purpose of producing the necessary partial vacuum to withdraw the sand from the box through the conduit.

35 3. The combination with a sand box, of an open ended conduit passing through an opening formed in the wall of the box, the inner extremity of the conduit being located within the box, directed downwardly and equipped with a communicating chamber, the lower end of the inner extremity of the conduit being arranged in suitable proximity to the bottom of the box.

40 4. The combination with a sand box, of a plurality of conduits suitably spaced around the circumference of the box and passing through openings formed in the wall thereof, both extremities of the conduits being open, their inner extremities extending downwardly, whereby they occupy 45 positions in suitable proximity to the bot-

tom of the box and equipped with communicating chambers, the latter being closed at their outer ends, the outer extremities of the conduits being closed in the lines of their axes and equipped with nozzles, whose 70 axes extend across the axes of the conduits, the nozzles being in communication with air under pressure for the purpose set forth.

5. The combination with a sand box, equipped with horizontally disposed conduits, both extremities of which are open, their outer extremities being equipped with air nozzles, whose axes are directed across the axes of the conduits, the conduits being provided with means applied to the opposite surfaces of the wall of the box to form 75 tight joints around the openings through which the conduits pass, the inner extremity of each conduit being equipped above its opening with a communicating chamber 80 closed at its outer extremity.

6. The combination with a sand box, having openings formed in the wall thereof and suitably spaced, open-ended conduits passing through these openings, said conduits 90 being longitudinally adjustable in the wall of the box, means being applied to the conduits on the opposite surfaces of the wall to form tight joints around the openings, the inner extremities of the conduits being 95 equipped with members vertically adjustable in order to bring the inner ends of the conduits in proper proximity to the bottom of the box, the outer extremities of the conduits being equipped with air nozzles whose 100 axes are directed across the axes of the nozzles, the outer extremities of the conduits being closed in the line of their axes.

7. The combination with a sand box, of conduits passing through openings formed in the wall of the box and suitably spaced in the circumference thereof, both extremities of the conduits being open, their inner extremities being downwardly directed to bring them in suitable proximity to the bottom of the box and equipped with communicating chambers closed at one end, the latter being closed at their outer ends, the outer extremities of the conduits being equipped 105 with air nozzles whose axes extend across the axes of the conduits, the latter being closed in the line of their axes and open at the top and bottom, and pipes in communication with the lower openings for conducting sand to the track rails, substantially as 110 described.

8. A locomotive sand box equipped with an open-ended conduit, one end being located within the box and the other being equipped with an air nozzle whose axis is directed across the axis of the conduit, the inner extremity of the conduit having a communicating chamber closed at one end.

9. The combination with a sand box mounted on a locomotive and equipped with 130

- open ended conduits passing through openings formed in the wall of the box, the conduits being horizontally disposed, one extremity of each conduit being located within 5 the box and equipped with a chamber closed at one end, while the other extremity extends beyond the box and is equipped with an air nozzle whose axis is directed across the axis of the conduit.
10. The combination with a sand box, of an open-ended conduit passing through an opening formed in the wall of the box, the inner extremity of the conduit extending into the central portion of the box and being 15 open to receive sand, and equipped with a chamber closed at one end, while the outer extremity of the conduit extends beyond the sand box and is equipped with an air nozzle for suction producing purposes.
20. 11. The combination with a sand box, of a plurality of conduits suitably spaced around the circumference of the box and so arranged that their inner extremities which are open, extend into the central portion of 25 the box and are equipped with communicating air chambers, while the outer extremities of the conduits extend beyond the box and are equipped with air nozzles, their outer ex-

tremities being also open by way of the nozzles and also opposite the nozzles for the 30 inlet of the air and escape of the sand under the influence thereof, respectively.

12. A locomotive sand box, equipped with an open-ended conduit, one end being located within the box and provided with a vertically adjustable member, while the other end of the conduit is equipped with an air nozzle, whose axis is directed across the axis of 35 the conduit.

13. A locomotive sand box, equipped with an open-ended conduit, one end being located within the box and the other extremity being closed in the direction of its axis, the inner extremity of the conduit above the 40 opening therein being equipped with a chamber, whose outer extremity is closed.

14. A locomotive sand box equipped with an open ended conduit longitudinally adjustable therein, one end being located within the box and equipped with a vertically adjustable member, the other being equipped with an air nozzle whose axis is directed 45 across the axis of the conduit.

In testimony whereof I affix my signature.

CHARLES A. PRATTE.
